COMBINED TABLE AND LAMP

Tody Foster, Sr., 202 Fabyan Place,
Newark, N.J. 07112

Filed July 11, 1968, Ser. No. 12,709

Term of patent 14 years

Int. Cl. D26—02

U.S. Cl. D48—20

FIG. 1

FIG. 2

FIG. 3

FIG. 4

FIG. 5

FIGURES 4 and 5 are left and right end elevational views of the combination of FIGURE 1.

The dominant features of my design reside in the portions shown in full lines.

I claim:

The ornamental design for a combined table and lamp, substantially as shown and described.
